DESIGN FOR A T-PIPE FITTING

Julian E. Stark, Wilmette, and Edward G. Schmidt, Chicago, Ill., assignors to Crane Co., Chicago, Ill., a corporation of Illinois

Application December 21, 1942, Serial No. 109,089

Term of patent 14 years

To all whom it may concern:

Be it known that we, Julian E. Stark and Edward G. Schmidt, citizens of the United States, residing at Wilmette and Chicago, in the county of Cook and State of Illinois, respectively, have invented a new, original, and ornamental Design for a T-Pipe Fitting, of which the following is a specification, reference being had to the accompanying drawing forming part thereof.

Fig. 1 is a side elevational view of a T-pipe fitting showing our new design.

Fig. 2 is a perspective view looking into the side outlet.

Fig. 3 is an end view looking into the run of the fitting.

Fig. 4 is a rear view of the fitting.

We claim:

The ornamental design for a T-pipe fitting, substantially as shown.

JULIAN E. STARK.
EDWARD G. SCHMIDT.
